ATTORNEY

WITNESS:

R. E. Voss.

UNITED STATES PATENT OFFICE.

LOUIS KALKBRENNER, OF WALL, SOUTH DAKOTA.

AUTOMATIC VALVE.

Application filed November 23, 1925. Serial No. 71,001.

This invention relates to a safety device for a gas line, the general object of the invention being to provide means for automatically closing a valve in the gas line 5 when the gas pressure falls so that when the pressure resumes, the gas cannot escape and do any damage.

This invention also consists in certain other features of construction and in the 10 combination and arrangement of the several parts, to be hereinafter fully described, illustrated in the accompanying drawings and specifically pointed out in the appended claims.

15 In describing my invention in detail, reference will be had to the accompanying drawings wherein like characters denote like or corresponding parts throughout the several views, and in which:—

20 Figure 1 is a view, partly in section, showing the parts in a position with the valve closed.

Figure 2 is a similar view, but showing the parts with the valve in open position.

25 Figure 3 is an end view.

In these views, 1 indicates the valve in the gas line 2 which is provided with the handle 3. A tube 4 is connected with the line by the coupling 5 and a telescopic casing 30 6 is attached to the tube, the movable part 6' of the casing being normally held in contracted position by the coiled spring 7 which has its ends connected with the ends of the two parts of the casing. The valve 1 is 35 placed in the main in advance of the coupling 5. A nipple 8 of rubber has one end closed and its open end is held over the opening in the tube 4 by the washer 9 so that the gas passing through the line will 40 enter the nipple 8 through the coupling 4 and thus expand the nipple and force the part 6' of the casing outwardly, as shown in Figure 2. This part is connected by the ear 10 with the handle 3 by a slot and pin 45 connection 11. In this position of the parts, the valve 1 is open and the gas flows through the main. If the pressure falls in the main, the spring 7 contracts and pulls the part 6' inwardly, thus closing the valve, as shown 50 in Figure 1, so that the gas is shut off and

it will not flow again until the handle 3 is moved to open position. When this is done, the expansion of the nipple 8 by the gas pressure will hold the valve in open position.

55 Thus I have provided simple means for automatically closing a gas valve when the gas pressure falls so that there is no danger of the gas escaping through the burners and the like when the pressure resumes.

I also desire to enclose the parts in a housing 12 to protect the parts from dust and I may also place oil, as shown at 13, in the housing, which covers the valve, to lubricate the parts. The housing is preferably 60 formed of two parts fastened together and has a door 14 which is held closed by the thumb nut 15.

65 It is thought from the foregoing description that the advantages and novel features 70 of my invention will be readily apparent.

I desire it to be understood that I may 75 make changes in the construction and in the combination and arrangement of the several parts, provided that such changes fall within the scope of the appended claims.

What I claim is:—

1. In combination with a gas main and its valve, a telescopic casing in communication with the main, a nipple in the casing 80 of flexible material held expanded by the gas pressure, said expansion of the nipple moving the telescopic member of the casing, a spring for holding the telescopic member in contracted position and means 85 for connecting said telescopic part with the valve.

2. In combination with a gas main and its valve, a telescopic casing having a nipple 90 of flexible material therein, a tube connecting the interior of the nipple with the gas main, a coiled spring connecting the two parts of the telescopic casing and acting to hold the same contracted, a handle on the valve, an ear on the movable part of the 95 casing and a slot and pin connection between the ear and said handle.

In testimony whereof I affix my signature.

LOUIS KALKBRENNER.
